UNITED STATES PATENT OFFICE.

ARTHUR L. STANFORD, OF CHICAGO, ILLINOIS.

RAIL-ANCHOR.

1,189,381.

Specification of Letters Patent. Patented May 11, 1915.

Application filed October 9, 1914. Serial No. 335,848.

To all whom it may concern:

Be it known that I, ARTHUR L. STANFORD, a citizen of the United States, residing at Chicago, in the county of Cook and State of Illinois, have invented certain new and useful Improvements in Rail-Anchors, of which the following is a specification:

The present invention relates to a device adapted to be applied to railroad rails for the purpose of preventing creeping of the same.

One of the objects of the present invention is to produce an anchor which may be termed universal; that is to make it of a single size and form whereby it can accommodate itself so as to fit and work efficiently upon any size of rail base.

A further object of the invention is to produce an anchor which is extremely cheap and simple of manufacture, and which can be shipped assembled, thus preventing their delivery to the purchaser in an incomplete condition.

A further object of the invention is to provide simple means for causing an efficient gripping of the anchor to the rail.

A further object of the invention is to arrange the anchor whereby it will act equally as well to prevent creeping of the rail in one direction as in the other.

The invention further consists in the features of construction and combinations of parts hereinafter described and claimed.

In the drawings: figure 1 is an elevation of the anchor of the present invention showing it applied to a rail base; Fig. 2 is a plan view of the anchor; Fig. 3 is a detail showing the manner in which the movable jaw of the anchor is fixed in position; and Fig. 4 is a detail of a slightly modified form of construction.

The device of the present invention, as stated, is intended to be affixed or applied to railroad rails for the purpose of preventing a creeping of the rails. As is well known in the art there is a tendency on the part of a rail to slide or creep under the influence of the passage of rolling stock over the same. Such creeping, if not checked, results in disorganization of road beds and misalignment of tracks and is extremely undesirable. Difficulty has been experienced in the art of rail anchors because of the fact that the size of rail bases varies considerable both as to breadth and thickness, cer-

tain roads will specify one size of rail, other roads another, and frequently the same road will have different sizes of rails in different portions of its trackage. The result of this is that rail anchor manufacturers are forced to carry a variety of sizes of anchor in stock, necessarily increasing the cost of production owing to the different rolls or patterns that are required to produce various size anchors, and further necessitating the carrying of a large stock on hand. A further difficulty has been experienced owing to the fact that rails of a similar poundage may vary in thickness of the base so that anchors designed for that particular class of rails, will not fit all rails of that size encountered.

In the present invention a rail anchor is designed which is capable of fitting any size of rail having any thickness of base, and which at the same time possesses all of the characteristics necessary to check the creeping action of the rails.

Referring to the drawings, and particularly to Fig. 1, the device is there shown as applied to a rail base 5 of a rail 6. The particular size of rail illustrated may be termed of the medium variety. This size is used merely for illustrative purposes, and the device could be shown equally as well in connection with any size of rail base that might be selected. The anchor consists of a body 7 of suitable material and the body terminates at one end in a depending flange 8 constituting a tie abutment. At the same end on which is located this tie abutment is also formed a gripping jaw 9, which is fixed with respect to the body of the anchor, and hence may be termed the fixed gripped jaw. This fixed jaw, as shown, has a seat 10 of V-shaped formation and the seat is cut away at its center as at 11 in Figs. 1 and 2, so that the acting portions of the jaw are at each end thereof. By placing the acting portion only at each end, there is assurance that the jaws will correctly engage with the side of the base of the rail. If the acting portions extended clear across the jaw it might happen owing to an irregularity in the casting, proper contact would not be made with the side of the rail base, but with the acting portion arranged at each end this danger is eliminated, since the acting portions comprise a relatively small surface. Forming the jaw in such manner does not effect the efficiency of it as a clamp-

ing or creeping resisting agency. There is a distinct advantage in forming this fixed jaw of a V-shape, because as is well known in the art, the thickness of rail bases differs even with the same size rail, and if the jaw were of the usual rectangular variety there might be difficulty encountered because the base of the rail would be too thick or too small to have the jaw properly engage the same. In the present construction, however, owing to the V-shape of the jaw such a difficulty could never arise, since whatever the thickness of the base might be, the jaw would properly engage the same.

15 The body of the anchor is formed with a floor 12, which, as shown, converges toward the opposite end from that end upon which is located the tie abutment and fixed gripping jaw, and from the point of convergence said floor continues on in what may be termed a bar or stem 13, which, as shown, is of split formation, and is angularly disposed with respect to the floor of the anchor; although from a constructive standpoint 20 this bar or stem is in reality a part of the floor. These upper and lower faces of the bar or stem 13 are threaded as at 14, and these threads receive a nut 15 which nut consists of a circular head 16 and a polygonal portion 17 extending to the rear thereof. This nut constitutes the movable gripping jaw of the anchor. The nut threads over the bar 13 and can travel up and down thereon as will be understood from the 25 drawing. In the case of a small rail the edge of the rail will terminate close to the end of the threads 14 and in order to bring the movable jaw 15 into engagement therewith, the nut is simply threaded down onto the stem until the head 16 comes into engagement with the base of the rail. In rails of larger dimensions the edge of the rail base will come farther up on the bar, and in order to fit the anchor to any size 30 of rail base, it is a mere question of moving the nut up or down upon the bar until the head engages the edge of the rail base.

From the foregoing it is observed that no matter what the size of the base of the rail 35 may be, the anchor of the present invention can be applied thereto without any difficulty and without any change in the size or construction of it. Therefore, one type of anchor can be applied to any size of rail base and it is therefore, a universal anchor.

From the drawing it will be seen that owing to the angular disposition of the bar 13, the head 16 of the movable gripping jaw will engage with the top edge of the rail base. The effect of pressure at this point will be to draw the fixed gripping jaw toward the rail base in an oblique direction; that is the fixed jaw will advance horizontally toward 40 the rail base and at the same time have a downward movement. Such a method of

drawing the fixed jaw will exert a powerful gripping action upon the rail and securely hold the anchor thereto. When the movable gripping jaw has been applied it can be locked in position by spreading the ends of the bars 13 apart, as in Fig. 3, so that by the very construction of the anchor a nut lock is provided which holds the movable gripping jaw in place, and no auxiliary appliances are required for this purpose. In Figs. 1, 2 and 3 the anchor illustrated has the bar 13 sheared into two parts after the formation of the body of the anchor. In the form shown in Fig. 4, however, the bar 13 is cast into two parts when the body of the anchor is formed. This leaves the slight opening 18 shown in this figure. The operation it is thought will be obvious from the previous description and the drawings. Briefly the anchor is applied to the rail with the tie abutment in contact with the tie. If the rail tends to creep in either direction the anchor will swing or cant, placing it in an oblique direction with respect to the rail with the result that one or the other acting portions of the fixed gripping jaw will be brought into gripping engagement with the rail and the creeping resisted. Of course, these acting portions of the fixed jaw are in engagement with the rail when the device is assembled, and are in sufficiently firm engagement so that when the creeping strains are exerted, the anchor instantly and automatically acts to resist such strain, so that the creeping is checked at its very inception.

The device is extremely cheap and simple of manufacture, consisting solely of two parts and these parts can be shipped together and in a manner so as to prevent separation during transit, thereby insuring that the anchors will be delivered to the purchaser in a complete condition for use.

I claim:

1. In a rail anchor the combination of a body portion, a fixed gripping jaw, that end of the body portion opposite from said fixed jaw being angularly disposed with respect to the remainder of the body portion, a threaded surface on the angularly disposed portion and a member arranged to travel upon said threaded surface and constituting a gripping jaw, substantially as described.

2. In a rail anchor comprising a body portion, a V-shaped fixed gripping jaw, that end of the body portion opposite from said fixed jaw being angularly disposed with respect to the remainder of the body portion, a threaded surface on said angularly disposed portion and a member arranged to travel on said threaded surface and constituting the movable gripping jaw, substantially as described.

3. In a rail anchor the combination of a body portion, a fixed gripping jaw at one

end of the body portion, said body portion tapering toward the opposite end and terminating in an angularly disposed integral threaded portion, and a member arranged to travel upon said threaded portion and constituting the movable gripping jaw, substantially as described.

4. In a rail anchor the combination of a body portion having a fixed gripping jaw at one end, a threaded portion at its opposite end extending obliquely with respect to the remainder of the body, a movable gripping jaw movable up and down upon said oblique portion, said movable jaw embodying a flat face arranged to engage the upper edge of the rail base, substantially as described.

5. In a rail anchor the combination of a body portion having an integral fixed gripping jaw at one end, said jaw being cut away at the center thereof whereby such cut away portion lies out of engagement with the rail base and engagement had between the jaw and rail base only at the extremities of the jaw, a movable gripping jaw at the opposite end of the rail base, and said movable jaw being movable relative to the fixed

jaw to vary the distance therebetween, substantially as described.

6. In a rail anchor the combination of a body portion having a fixed gripping jaw at one end, said jaw being cut away at the center thereof whereby such cut away portion lies out of engagement with the rail base and engagement had between the jaw and the rail base only at the extremities of the jaw, and a movable gripping jaw at the opposite end of the rail base.

7. In a rail anchor, the combination of a body portion, an integral fixed gripping jaw at one end of the body portion, a threaded stem at the opposite end of the body portion extending beyond the rail base, a movable gripping jaw, the acting face of the movable gripping jaw being angularly disposed with respect to the upper edge of the rail base, and said acting face engaging the edge of said base, and extending obliquely thereacross, substantially as described.
